UNITED STATES PATENT OFFICE.

GOTTWALT SIEBER, OF PLAUE, GERMANY.

SHUTTLE EMBROIDERING MACHINE.

1,419,317.

Specification of Letters Patent. Patented June 13, 1922.

Application filed September 10, 1921. Serial No. 499,858.

To all whom it may concern:

Be it known that I, GOTTWALT SIEBER, a citizen of the Republic of Saxony, residing at Plauen, in Saxony, have invented certain 5 new and useful Improvements in Shuttle Embroidering Machines, of which the following is a specification.

This invention relates to a device in shuttle embroidering machines destined to do 10 away with the friction formerly existing between shuttle and shuttle path, and it also insures a very reliable loop-catching and consequently a safer fixing of the stitches on the shuttle side than hitherto was possible.

15 The new and characteristic feature of the device consists in that the shuttles with the thread contained therein are shifted, not above the embroidering needles, but to and fro below the latter and are lying on their backs. The weight of the shuttle bodies, therefore, does not bear on the path as formerly and any wear of the shuttles seems nearly completely excluded, thus enabling the manufacture of a lasting good product.

20 Besides this the introduction of the shuttle point into the loop formed by the rocking movement of the needle-bar is facilitated. In the devices of known construction the thread loops always were formed on the 30 upper side of the needles and projected beyond the shuttle guide path far enough to enable the introduction of the shuttle. As a result the loops had a great tendency to fall down so that the shuttles then did not slide 35 into the loops, but shot over them.

If, however, the shuttles are arranged in the position as stated above, the thread-loops will always hang down so that the shuttle will be sure to pass through it and missing 40 will be absolutely impossible.

A further disadvantage in the known construction is that the needle channels in the path of the shuttles easily fill up with waste or dirt and in that case the formation of the 45 loops becomes almost impossible. But in the present construction the shuttle path is below the needle channel so that nothing can get into the needle channels from above, and the latter are free of dirt or waste and re- 50 main so always.

In the accompanying drawings an embodiment of my invention is represented, Fig. 1 being a cross-section and Fig. 2 a front view of the needle and shuttle arrangement of an embroidering machine.

Similar to well known devices the introduction of the needle thread into the fabric in the present device also is brought about by the embroidering needle 2 fixed to the needle-bar 1. At the back side of the fabric 60 a bar 4 is provided having needle channels 3 and below which the shuttles 5 reciprocate horizontally. The bar 4 is connected to an angle bar 7 by means of a stitch-plate 6 extending in the longitudinal direction of the 65 machine. The shuttles 5 are each placed in a shuttle frame or basket 8 fixed to a slide 9 in such a manner as to render replacement or exchange of the shuttle easy. The point of the shuttle rests on a finger 10 projecting 70 from and forming part of the shuttle-basket 8, and the back 11 of the shuttle is held by an annular projection 12. Both the arm 10 and the projection 12 are as shown joined to the slide 9.

To permit access to the inspection hole 14 of the shuttle 5 the basket 8 is cut out as at 15. The slide 9 is carried by the driving-bar 16 adapted to move to and fro thus transmitting the reciprocating movements of the lat- 80 ter to the shuttles.

What I claim and desire to secure by Letters Patent is:—

1. In a shuttle embroidering machine, the combination with horizontally reciprocating 85 needles and a bar having channels in front of said needles, of means reciprocating below the channels of said bar horizontally and at a right angle to said needles and shuttles supported in said means to extend longitudinally of the path of said means. 90

2. In a shuttle embroidering machine, the combination with horizontally reciprocating needles and a bar having channels in front of said needles, of means reciprocating horizontally below the channels of said bar at a 95 right angle to said needles including frames or baskets and a shuttle supported in said frame to extend longitudinally of the path of said frames.

3. In a shuttle embroidering machine, the combination with horizontally reciprocating needles and a bar having channels in front of said needles, of frames or baskets horizontally reciprocating at a right angle 105 to said needles, a shuttle deposited in each of said frames to extend longitudinally of the path of the latter, each of said frames having means to engage the point and back of a shuttle. 110

4. In a shuttle embroidering machine, the combination with horizontally reciprocating needles, and a bar having channels in front of said needles, of a driving bar movable 5 horizontally at a right angle to said needles and frames supported on said bar to extend below said channels, a shuttle removably supported in each frame so as to face the underside of said channelled bar, each of 10 said frames being adapted to embrace the point and the back of a shuttle.

5. In a shuttle embroidering machine, the combination with horizontally reciprocating needles, and a bar having channels in front 15 of said needles, of a driving bar movable

horizontally at a right angle to said needles, and frames supported on said bar to extend below said channels, and a shuttle having an inspection hole and removably supported in each frame so as to face the underside of 20 said channelled bar, each of said frames being adapted to embrace the point and the back of a shuttle, and being cut out to expose said inspection hole.

In testimony whereof I affix my signature 25 in presence of two witnesses.

GOTTWALT SIEBER.
